UNITED STATES PATENT OFFICE.

GEORGE H. GIBSON, OF MONTCLAIR, NEW JERSEY.

HOT-WATER HEATING SYSTEM.

1,116,690.

Specification of Letters Patent. Patented Nov. 10, 1914.

Application filed March 9, 1914. Serial No. 823,296.

To all whom it may concern:

Be it known that I, GEORGE H. GIBSON, a citizen of the United States of America, residing in Montclair, in the county of Essex and State of New Jersey, have invented certain new and useful Improvements in Hot-Water Heating Systems, of which the following is a true and exact description, reference being had to the accompanying drawings, which form a part thereof.

My present invention relates to heating systems in which the heating medium is hot water.

15 The object of the invention is the production of a simple, reliable and effective heating system in which a heater like the well known open feed water heaters for heating boiler feed water or the like may be advantageously employed for heating the water circulated through the radiators by the direct action on the water of the steam. In the open feed water heaters referred to, a heating chamber is provided into which 20 the water to be heated, and steam for heating it, are both admitted, suitable overflow connections being provided to insure the presence of a steam space in the upper portion of the chamber.

30 More specifically, my invention relates to a system of this character comprising a pump by which the hot water is withdrawn from the heater and caused to flow through the radiating system proper and is returned 35 thereto from the heater.

A more specific object of my invention is to provide a system of the particular kind referred to with controlling means, manually or otherwise actuated, whereby the 40 circulation through the system as a whole or through some portion thereof may be varied to thereby vary the heating effect, and to provide the system with other means responsive to the variations in the circulation produced by the first mentioned means for automatically effecting a further regulation of the system for the purpose of avoiding unnecessary loads on the pump.

The various features of novelty which 50 characterize my invention are pointed out with particularity in the claims annexed to and forming a part of this specification. For a better understanding of the invention, however, and of the advantages possessed 55 by it, reference should be had to the accompanying drawings and descriptive matter

in which I have illustrated and described forms in which my invention may be embodied.

Of the drawings: Figure 1 is a diagrammatic elevation of one form of apparatus in which my invention may be embodied; Fig. 2 is a sectional elevation of one of the valves forming a part of the apparatus shown in Fig. 1; Fig. 3 is a sectional elevation of another valve and its operating mechanism forming a part of the apparatus shown in Fig. 1; Fig. 4 is a diagrammatic elevation of another form of apparatus in which my invention may be embodied; and Fig. 5 is a sectional elevation of a valve forming a part of the apparatus shown in Fig. 4.

In the drawings, and referring first to the apparatus shown in Figs. 1, 2 and 3, A represents the heater proper, which is of a type in common use and well known as an open feed water heater. As shown, the heater comprises a chamber having a steam inlet pipe B leading to the chamber through an oil separator B', as is usual, a cooling water makeup supply pipe C leading into the upper end of the chamber, splash trays or baffles D located in the upper portion of the chamber beneath the discharge from the pipe C, and outlet pipe E for hot water, and a float controlled overflow or waste connection F of the usual type for limiting the height of water level in the chamber. A stand pipe G leading from the upper end of the heater and controlled by the loaded relief valve G' is employed as shown to limit the steam pressure in the heater. The outlet pipe E from the heater is connected to the inlet of a circulating pump X, which, as shown, is a centrifugal pump. The outlet from the pump X is connected to the pipe H which forms the riser supplying water to the radiators K. As shown, the pipe H proper extends to the top of the circulating system proper where it connects with the pipe H' which forms the supply pipe proper for the radiators. The pipe H includes one or more suitable check valves H'. The outlets of the radiators are connected to the return pipe L, which advantageously contains a seal loop L', and leads back to the heater, opening to the latter in a position to discharge onto the splash trays D. The usual hand regulating valves K' should be provided in the outlet connections of the radiators or in their inlet con-

nections, or preferably, as shown, in both connections to each radiator. The flow back to the heater through the return pipe L is controlled by a valve O comprising a casing 5 having its inlet and outlet chambers connected by a valve seated port O' controlled by a valve disk O². The pressure of the water admitted to the valve casing through the return pipe L acts against the valve disk O² in a direction tending to move the latter into its open position. The valve disk is normally urged toward its seat by means of a spring O³ acting between the casting of the valve and the nuts O⁴ threaded on and adjustable along the threaded valve stem O', which projects through the exterior wall of the valve casing proper. A plate-like member O⁵ is secured to the valve casing proper by the studs or posts O⁶. Secured 10 to the member O⁵ is a chambered member formed with a cup-shaped member O⁶, the bottom of which is closed by a flexible diaphragm O⁹. Pressure fluid is supplied to the interior of the chamber O⁶ by a pipe P. This 15 pipe is connected by a valve R to a pipe P' containing a fluid under pressure, as compressed air. The valve R comprises a casing having its inlet and outlet chambers separated by a valve seated port R' which is 20 normally closed by a ball valve member R². The latter is lifted from its seat, and the port R' thereby opened, by means of an actuating member S projecting into the casting of the valve R and responsive to the 25 pressure in the upper portion of the circulating system. As shown, the lower end of the member S rests on a flexible diaphragm T' located in the diaphragm chamber T which is connected to the upper end of the 30 riser H. In the arrangement shown in Fig. 1, the motor Z, driving pump X, is a steam turbine, and the supply of steam to the turbine Z is controlled by the manually adjustable throttle valve OA. The purpose of 35 the valve O is to so throttle the flow through the return pipe L that the radiators will be kept full of water. This requires, in general, with the apparatus shown in Figs. 1, 2 and 3, that the closing force exerted on the valve disk O² by the spring O³ shall be 40 as great as the opening force of the water on the valve disk O² when the water pressure in the inlet chamber of the valve O corresponds to the difference in height between 45 the level of the valve and the level of the uppermost portion of the circulating system to be kept flooded, as it will when the flow through the circulating system is slow and the frictional resistance to the downward flow of the water is negligible. As 50 the rapidity of flow through the circulating system is increased, however, the water pressure in the inlet chamber of the valve O will become less than the static head corresponding to the difference between the

level of the valve O and the water level in the circulating system owing to the frictional resistance to the downward flow of the water through the radiators, valves and piping. Indeed, this resistance may be great 55 enough, when a very rapid circulation is had, to absorb all or practically all of the static head. If the force exerted by the spring O³ on the valve disk O² is not reduced or neutralized when the pressure of the water on the valve disk O² is thus reduced, it becomes necessary to increase the pressure of the water at the top of the circulating system in order to secure the desired circulation and this requires an increase in the 60 load on the circulating pump, which is undesirable, especially as it occurs at a time when the load on the pump is already heavy. In the operation of the apparatus shown in Figs. 1, 2 and 3, however, when the pressure to which the diaphragm T' is subjected, rises above the value which it is desired to have in the portion of the circulating system to which the chamber T is connected, the movement then imparted to 65 the diaphragm T' and the rod S causes the ball R² to be lifted off its seat R', and thus permit pressure fluid to flow from the pipe P' through the pipe P into the chamber O⁶. The pressure of the fluid in the chamber O⁶ 70 tends to depress the diaphragm O⁹ which engages the upper end of the valve stem O', and thereby neutralizes the action of the spring O³ on the valve disk O² in whole or in part, depending on the pressure in the casting O⁶. This reduces the retarding or throttling effect of the valve disk O² and tends to correspondingly reduce the pressure at the top of the circulating system. As shown, a restricted leakage vent O¹⁰⁰ is formed in the 75 wall of the chamber O⁶ and as soon as the valve R² seats the pressure in the chambered casing begins to fall more or less quickly, depending on the size of the leakage port O¹⁰⁰. The pressure within the chamber O⁶ 80 will vary accordingly from atmospheric pressure to a pressure approaching that of the pipe P', depending upon the extent to which the valve R² is lifted off its seat and the duration of the intervals during which 85 it is held off its seat. The system shown in Figs. 1, 2 and 3 is especially suitable for use in heating factories or the like, wherein the distribution of the heating fluid among the different 90 radiators or branches of the radiating system proper is constant or practically so, the valves K' of the different radiators not being adjusted in response to ordinary temperature variations. In a system of this sort it, 95 is common to regulate the total circulation by adjusting the throttle valve OA or other device controlling the motor driving the circulating pump X either manually or thermostatically in general response to the 100

changes in the temperature of the external atmosphere. The system shown in Figs. 1, 2 and 3 is especially well adapted for use in this manner, for as the speed of the pump is increased, the strangle valve O is adjusted to offer less resistance to the flow back to the heater from the radiators as is desirable at this time. The apparatus shown in Figs. 1, 2 and 3 is less desirable where valves 10 K' controlling the flow through the individual radiators are constantly being adjusted at the volition, for instance, of the occupants of different rooms heated by the different radiators. In such a case it is desirable, however, to automatically compensate for the changes manually made in the distribution of flow through the circulating system, and this may well be brought about by employing means responsive to the accumulation of wall or pressure at the top of the circulating system to control the speed of the circulating pump. One arrangement for this purpose is shown in Figs. 4 and 5.

The system shown in Fig. 4 differs from that shown in Fig. 1 in the omission of the automatic strangle valve O in the return line from the radiators, and in the replacement of the throttle valve OA in the steam line of the pump driving motor Z by an automatic valve OB controlled by means responsive to the pressure or accumulation of water at the top of the circulating system. As shown in Fig. 4, moreover, the last mentioned means is specifically different from the corresponding means shown in Fig. 1, but this has nothing to do with the essential difference in type between the system shown in Fig. 1 and that shown in Fig. 4. Advantageously in most cases a valve OC, which 35 may be a plain or throttle valve, is located in the return pipe from the radiators. The valve OB may be and is shown as being essentially the same as the valve O of Fig. 2, except that the valve member O¹⁰ of Fig. 4 is balanced and is moved toward and not away from its seat by an increased pressure in the chamber O⁸, and no leakage port O¹⁰⁰ from the chamber O⁸ is provided. The means shown in Fig. 4 for controlling the 40 valve OB comprises a tank JA located at the top of the circulating system and receiving the discharge from the riser pipe H. Water passes from the tank JA to the radiators through the pipe HA'. A float J¹⁰ 45 located within the tank JA, and responsive to the rise and fall of the water level in the tank JA, operates a valve U, opening and closing the latter as the water level in the tank JA falls below and rises to a predetermined level. The valve U when open connects a pipe W to the tank JA. The pipe W is connected to a pipe W', containing water under pressure, by the restricted orifice W². A branch pipe W³ runs from 50 the pipe W to the pressure chamber in the

casing O⁸ of the turbine controlling valve OB. The constant though restricted flow of water into the pipe W through the restricted port W² tends to build up the pressure in the pipe W, and branch pipe W³ and valve chamber O⁸ to an equality with the pressure in the pipe W', so long as the valve U is closed. In consequence, the pressure in the chamber O⁸, when the valve U is closed, keeps the valve disk O¹⁰ against its seat. When the water level falls in the tank JA sufficiently, however, to lower the float J¹⁰ and thereby open the valve U, the flow of water which then takes place from the pipe W into the tank JA reduces the pressure in the pipe W, branch pipe W³ and valve chamber O⁸, and the valve disk O¹⁰ then rises from its seat, more or less, depending on the extent to which the pressure in the chamber O⁸ is reduced. The pressure in the chamber O⁸ will obviously depend at this time on the extent to which the valve U is open and the duration of the intervals during which the valve U is kept open. Y represents an overflow connection 90 leading back to the heater from the tank JA and opening to the latter, at a level above that at which the valve U will be closed by the float J¹⁰. Advantageously, as shown, the pipe Y is formed with a loop Y' providing a water seal, and with a vent connection Y² from the top of the leg of this loop which is connected to the heater.

With the system shown in Fig. 4 the distribution of flow through the different radiators and, in general, the amount of flow through the system as a whole, is constantly being altered by the separate adjustments of the valves K controlling the flow through the individual radiators. The valve OB 100 and its controlling means act however to so regulate the speed of the circulating pump X that the pressure at the top of the circulating system necessary to effect the desired circulation through the different radiators 110 will be constantly maintained on the one hand, while, on the other hand, no unnecessarily large load is imposed on the pump at any time.

While in accordance with the provisions 115 of the statutes I have illustrated and described the best forms of apparatus embodying my invention now known to me, it will be apparent to those skilled in the art that the invention set forth and claimed 120 may be embodied in apparatus of different form from that disclosed herein, and that under certain conditions certain features of the invention may be used with advantage without a corresponding use of other features.

Having now described my invention, what I claim as new and desire to secure by Letters Patent, is:

1. In a hot water heating system com- 130

prising a circulating system, including a return piping discharging against a pressure less than the static head in the return piping at the point of discharge when said 5 circulating system is filled with water to the desired extent, and means for restricting the flow through the return piping at a point adjacent the discharge therefrom, said means including provisions for automatically 10 decreasing the restrictive effect produced as the flow through said circulating system increases.

2. In a hot water heating system comprising a circulating system including a return piping discharging against a pressure less than the static head in the return piping at the point of discharge when said circulating system is filled with water to the desired extent, and means for restricting 15 the flow through the return piping at a point adjacent the discharge therefrom said means including pressure responsive provisions automatically decreasing the restrictive effect produced as the pressure in an 20 upper portion of said circulating system increases.

3. In a hot water heating system the combination with an open water heater, of a 25 circulating system comprising a pump, and piping through which water is drawn from the heater by the pump and forced to a level substantially above that of the heater and returned therefrom to the heater, of a valve 30 located in the return portion of said piping adjacent said heater for retarding the flow back to the heater, and means responsive to the pressure in an upper portion of said 35

circulating system for reducing the throttling effect of said valve as the last mentioned pressure increases.

4. In a hot water heating system, the combination with an open water heater, of a 40 circulating system comprising a pump, and piping through which water is drawn from the heater by the pump and forced to a level substantially above that of the heater and returned therefrom to the heater, of a 45 motor valve located in the return portion of said piping adjacent said heater for retarding the flow back to the heater and comprising a pressure chamber and means responsive to the pressure in an upper portion of said 50 circulating system for varying the pressure in said chamber and thereby varying the throttling effect of said valve as the pressure in the upper portion of the circulating system increases.

5. In a hot water heating system, the combination of an open water heater, a radiating system, flow restricting means regulating the resistance to flow through the radiators to the heater, pumping means for withdrawing water and delivering it to the radiators, one of said means being regulable, and mechanism for automatically 55 regulating the other of said means as the pressure in the upper portion of the circulating system varies in response to an adjustment in said regulable means.

GEORGE H. GIBSON.
